FABRIC NAPPING MACHINE

Harry Fleisher, Watertown, Conn., assignor to
 Princeton Knitting Mills, Inc., Watertown,
 Conn., a corporation of Connecticut

Application October 21, 1938, Serial No. 236,311

16 Claims. (Cl. 26—29)

This invention relates to the manufacture of fabrics, and more particularly to a machine for napping the exterior surface of a tubular fabric made on a circular knitting machine.

One object of this invention is to provide a machine of this type having a plurality of fabric napping devices arranged in spaced relation around the tubular fabric, and each of which is readily adjustable in respect to the fabric while the fabric is in operating position.

A further object is to provide a napping machine of the above nature which is provided with improved means for helically rotating the tubular fabric while being napped, improved take-up mechanism to wind up the napped fabric, and common means for driving said rotating means and take-up mechanism.

A still further object of this invention is to provide a fabric napping machine of the above nature which is relatively simple in construction, inexpensive to manufacture, which will produce an attractive, ornamental and uniform napped surface on the fabric, and which will be very efficient and durable in use.

With these and other objects in view, which will appear as the description proceeds, there has been illustrated on the accompanying drawings a machine in which the invention may be conveniently embodied in practice.

In the drawings:

Fig. 1 represents a front view of the fabric take-up mechanism which is located above the napping mechanism, certain parts being shown in section to illustrate the interior construction thereof.

Fig. 2 is a broken vertical sectional view through the napping mechanism, and also showing the bottom receptacle for carrying the supply of unnapped fabric, the section being taken on the plane 2—2 of Fig. 4.

Fig. 3 is a sectional view of a portion of the take-up mechanism shown in Fig. 1, looking upwardly in the direction of the arrows 3—3.

Fig. 4 is a top plan view of the napping mechanism, looking downwardly from a plane indicated by the arrows 4—4 in Fig. 2.

Fig. 5 is a top plan view of the fabric supply receptacle and driving mechanism, looking downwardly from the plane 5—5 of Fig. 2.

Fig. 6 is a sectional view taken on the plane 6—6 of Fig. 1.

Fig. 7 is an enlarged sectional view taken on the plane 7—7 of Fig. 4.

Fig. 8 is a side view of the parts shown in Fig. 7 looking in the direction of the arrow 8 thereof.

Fig. 9 is a side view of one of the centralizing and guiding rollers and the support therefor, looking in the direction of arrow 9 in Fig. 4.

Fig. 10 is a side view of another roller, looking in the direction of the arrow 10 in Fig. 4.

Fig. 11 is a view similar to Fig. 10, showing the addition of a stationary napping brush adjustably supported on the roller support shown in Fig. 10.

Fig. 12 is an enlarged fragmentary section 10 through a modified construction including an inflatable rubber tube which permits the drag of the tensioning means to be adjusted.

Referring now to the drawings wherein like reference numerals denote corresponding parts 15 throughout the several views, the numeral 10 (see Fig. 1) indicates an upper floor of a building, the numeral 11 (see Fig. 2) a middle floor, and the numeral 12 (see Fig. 2) a lower floor below the floor 11. The machine of this invention extends 20 between two superposed rooms of a building in order to accommodate the long length of the tubular fabric 13 being napped thereby. The fabric supply mechanism is supported upon the lower floor 12 by legs 14, below the napping mechanism which is supported upon the middle floor 11 by legs 15, and the top fabric take-up mechanism which is supported from the upper floor 10 as by depending brackets 16.

Receptacle for unnapped fabric

30 The tubular knitted fabric 13, before being napped, is adapted to be manually piled or stacked in a loosely piled bellows-like condition in an open-top receptacle 17 (see Figs. 2 and 5), which 35 surrounds and is connected with the lower end of a shaft 18 extending vertically through the center of the machine.

In order to facilitate the stacking of the fabric into the receptacle 17, provision is made of a 40 smooth surfaced domed cap 19 (shown in dotted lines in Fig. 2), said cap being removably secured on the upper end of said shaft 18. The receptacle 17 rests upon a flat circular plate 20, which in turn is secured upon an annular rack 21 having gear teeth 22 formed upon its outer periphery. The rack 21 is rotatably mounted in a circular recess 23 formed in a bed plate 24 supported by the legs 14. The lower end of the shaft 18 is secured in a bushing 25 in turn secured to a bar 45 26 secured to and extending diametrically across the rack 21.

The rack 21 is adapted to be rotated by a motor 27 connected by a belt 28 running over pulleys 29 and 30, the latter being secured on a shaft 50 31 journaled in brackets 32 and 33 secured on

a cross-bar 34 connected to the legs 14 by brace bars 35 and 36 (see Fig. 5).

In order to drive the overhead fabric take-up mechanism from the motor 27, provision is made of a bevel gear pinion 37 secured on one end of the shaft 31 and meshing with a horizontal bevel gear 38 secured on an elongated upwardly-extending shaft 39 journaled at its lower end in a bushing 40, mounted on the cross-bar 34. The shaft 39 passes upwardly through the bed plate 24, and has secured thereto a gear 41 meshing with the teeth 22 on the rack 21, whereby the supply receptacle 17 with the piled-up fabric 13 carried therein will be slowly rotated. The shaft 39 extends upwardly from the gear 41 through the middle floor 11 and is connected by means of a universal joint 42 to an inclined shaft 43 which extends upwardly to the fabric take-up mechanism suspended from the upper floor 10. The shaft 39 is journaled in a bracket 44 (Fig. 9) secured to a bed plate 45 which supports the napping mechanism, and in turn is supported by the legs 15 resting on the middle floor 11.

Fabric take-up mechanism

The upper end of the inclined shaft 43 is journaled in a bracket 46 extending outwardly from a stationary bed plate 47 supported on the ceiling 10 by the legs 16 (see Figs. 1, 3 and 6). A bevel gear 48 secured on the end of the shaft 43 is in mesh with a bevel gear 49 secured on the outer end of a shaft 50 journaled in brackets 51 and 52 mounted on the bracket 46 and the bed plate 47 respectively. A spur gear 53 is secured on the inner end of the shaft 50 and has its teeth in mesh with the teeth 54 of a circular ring-shaped rack 55 mounted to slidably rotate on the fixed ceiling bed plate 47.

Depending from the rack 55 at diametrically opposite points are a pair of standards 56 and 57 which are connected to a cross-bar 58 having a pair of parallel downwardly extending arms 59 and 60. The arms 59 and 60 are each provided with lengthwise slots 61, in which bearing blocks 62 are slidably supported. The bearing blocks 62 are adapted to be clamped in vertically adjusted positions by a nut 63, and said bearing blocks support the opposite ends of a cross-shaft 64 journaled therein.

Mounted on the shaft 64 is a spindle 65, upon which is wound the roll of fabric 13 after being napped. The shaft 64 is rotated by a round belt 66 led over a pulley 67 secured on one end of the shaft 64 and over a pulley 68 secured on a horizontal stud shaft 69 journaled in the arm 59 and a bracket 70 mounted on the cross-bar 58.

The shaft 69 has at its inner end a bevel gear 71 which meshes with a bevel gear 72 rotatably mounted on the lower end of a vertically depending stationary shaft 73. The upper end of the shaft 73 is rigidly secured in a bushing 74 secured to the upper floor 10.

By means of the above construction it will be seen that when the napped fabric 13 is received on the roller 64, it will be tightly wound into a roll 75 with uniform tension irrespective of the increase in diameter thereof. This is due to the fact that the belt 66 is permitted to slip on the pulleys 67 and 68 to compensate for any increase in fabric take-up speed due to the increase in diameter as the roll of fabric builds up.

The fabric 13 is pulled upwardly from the receptacle 17 through the napping mechanism by means of a driven roller 76 and two idle rollers 77 and 78 located above and below said roller 76, respectively. The opposite ends 79 and 80 of the

roller 76 are journaled in the bars 59 and 60, respectively, and said roller 76 is driven by a cone pulley 81 secured to the shaft end 78 and connected by a belt 82 to a cone pulley 83 secured on the shaft 69. The roller 77 has its shaft ends 84 loosely mounted in the slots 61 in the arms 59 and 60 above the roller 76 and the weight of said roller 77 presses the fabric 13 against the driven roller 76. The roller 78 also has its shaft ends 85 loosely journaled in the bars 59 and 60 and is disposed out of alignment with the roller 76 in a position to permit the fabric 13 to lead upwardly thereto substantially in vertical alignment with the axes of the rollers 76 and 77. Power for driving the central roller 76 at constant speed may be supplied from any suitable source, not shown.

The fabric 13 is guided upwardly to the roller 78 from the napping mechanism by means of an open double-arm spreader frame 86 which serves to flatten out the fabric 13 and position its edges accurately between a pair of guide rollers 87 and 88 which are mounted on a pair of parallel spindles 89 carried by a horizontal bracket 90 (see Fig. 6). The brackets 90 are slidably mounted on a cross-rod 91 which extends between the lower ends of the bars 59 and 60, and on which they are adjustable to properly space apart the rollers 87 and 88 by means of a screw-threaded rod 92. The rod 92 is adapted to be manually rotated in bearings in the bars 59 and 60 by means of a hand wheel 93 secured at one end to said rod 92.

The screw threads on the opposite ends of said rod 92 are oppositely pitched to correspond with similarly pitched threads in the bores 94 of the brackets 90 so that when the handle 93 is turned, said brackets 90 will simultaneously slide in opposite directions along the rod 91 to cause the rollers 87 and 88 to adjust the alignment of the tubular fabric 13 in respect to the take-up spindle 65.

Napping mechanism

The mechanism for guiding and supporting the fabric while being napped, and which will be assembled upon the shaft 18, is as follows: (see Figs. 2 and 4)

First.—A fabric tensioning disc 95 will be locked to the shaft 18, as by a key, in a position above the floor 11 and below the bed plate 45. The disc 95 has a deep annular groove 96 formed in its periphery whereby spaced apart rims 97 and 98 are formed, around which the fabric is adapted to engage. To provide tension or "drag" upon the fabric sufficient to keep it taut from the disc 95 to the roller 76, a coiled wire spring 99 is stretched outside the fabric 13 and serves to press the fabric tightly against the rims 97 and 98.

Second.—A pair of spaced flat discs 100 and 101 are keyed to the shaft 18 above the bed plate 45 by having hub portions 102 and 103, respectively. The discs 100 and 101 are spaced apart sufficiently to provide a space therebetween, over which a portion of the fabric 13 may be stretched across the peripheries thereof.

Third.—A flanged cylindrical member 104 is keyed to the shaft 18 above the upper disc 101. The periphery of the member 104 has an annular groove 105 surrounded by upper and lower flanged rings 106 and 107, against which the fabric is adapted to engage.

Fourth.—A spreader frame 86 is detachably mounted for use during the napping operation upon the upper end of the shaft 18 (in place of

the dome-shaped cap 19 which is only used to facilitate the loading of the unnapped fabric into the machine), and is secured thereto by a knurled flanged nut 108.

From the above it will be understood that the power will be supplied by the motor 21 through the shafts 39, 41, 18 and 73 to simultaneously rotate the receptacle 17, the disc 95, the discs 100 and 101, and the cylindrical member 104 as a unit. The napped knitted fabric will at the same time be wound upon the spindle 65 by the mechanism previously described.

While the tubular fabric 13 is being drawn upwardly from the receptacle 17, it will be continuously napped by a plurality of napping devices mounted upon the bed plate 45 and arranged to act upon the outer surface of the continuously-helically upwardly-moving tubular fabric, all of said devices being driven by a motor 109 mounted on the middle floor 11 (see Fig. 2). From the motor 109 a belt 110 is led over a pulley 111 mounted on the shaft of the motor 109 and also over a pulley 112 secured on the outer end of one of eight horizontal shafts 113 supported by and journaled in one of eight brackets 114 mounted on the bed plate 45, as clearly shown in Figs. 2, 4, 7 and 8.

The driven shaft 113 has a pinion gear 115 secured upon its inner end, the teeth of which are in mesh with the teeth of a ring-shaped or circular rack 116 mounted upon the bed plate 45, the rack 116 being adapted to be rotated by said gear 115 for driving eight rotary napping brushes 120, to be described below. The eight brackets 114 and shafts 113 are equally spaced about the bed plate 45. All of the brushes 120 will be simultaneously rotated by the rotation of the rack 116 driven by the motor 109 through the belt 110 and the pulleys 111 and 112.

Twisting napping brushes

Each of the shafts 113 has a screw threaded opening provided in its inner end (as best shown in Fig. 7), into which a screw threaded shank 117 of a fabric napping brush holder 118 is screwed. A lock nut 119 is associated with each shank 117 to securely hold each shank in its adjusted position relatively to the shaft 113. Provision is also made on each brush holder 118 of a flat faced napping brush 120 mounted in a block 121 which is adjustably secured thereto by means of a thumb screw 122, which passes through the flat side 123 of a tongue 124 formed on said block 121 to clamp an inclined half-dovetail-shaped section 125 against a similarly formed side 126 of a slot 127 provided in the holder 118. By means of the tongue 124 and slot 127 the brush 120 may be adjusted laterally across the axis of the shaft 113, and by means of the screw-threaded shank 117 and the screw-threaded opening in the shaft 113, the brush 120 may be adjusted axially of the shaft 113 to control the pressure of the brush 120 upon the portion of the fabric 13, which is stretched between the discs 100 and 101.

By means of the above construction it will be seen that the brushes 120 will all rotate simultaneously on horizontal axes which are disposed radially in a common plane at right-angles to the axis of the shaft 18, whereby said brushes 120 will act on the fabric 13 to nap it on flat areas by a circular twisting movement while it engages the exterior surface of the upwardly helically moving tubular fabric.

Cylindrical napping mechanism

In order to additionally nap the exterior of the tubular fabric 13, in a direction parallel to the shaft 18 and tangent to the tubular fabric 13, provision is made of a plurality of rotatable cylindrical napping brushes 128 (four in this instance), said brushes being equally spaced apart and each being mounted on four shafts 129, supported by four angle brackets 130, respectively (see Figs. 2, 7 and 8). A pulley 131 drivingly connected to the brush 128 of one of the shafts 129 is connected by a belt 132 to a pulley 133 secured on the upper end of a vertical driving shaft 134, mounted in an upper arm of the bracket 114. A bevel gear 135 is secured on the lower end of the shaft 134 and is in mesh with a bevel gear 136 secured on the horizontal pulley-driven shaft 113, whereby the vertical shaft 134 will be driven therefrom.

The four angle brackets 130 are each adjustably mounted on the screw-threaded ends 137 of horizontal rods 138 which are adapted to be locked in adjusted position thereon by nuts 139 and 140. This adjustment is provided to permit desired variations in the pressure of the cylindrical brush 128 upon the exterior of the fabric 13. The horizontal rods 138 are each in turn slidably and rotatably mounted upon a bar 141, and are secured thereto in any desired adjusted position by a set screw 142.

By means of this construction it will be seen that both the vertical and lateral positions of the respective brushes 120 in respect to the fabric 13 may be readily controlled. The bar 141 extends outwardly from a ring 143 which rotatably encircles a hub 144 formed on the bracket 114 and is secured thereto by a set screw 145. Adjustment of the ring 143 on the hub 144 is necessary to compensate for the vertical adjustment of each disc brush 120.

Centralizing and guiding mechanism

To insure that the shaft 18 is centralized and the disc and cylindrical brushes 120 and 128 will rotate steadily and without vibration, and thus insure even and uniform stretching of the fabric thereabout, provision is made of a plurality of rollers 146 and 147 adjustably mounted in standards 148 and 149, respectively, arranged uniformly about the bed plate 45. Eight rollers 146 are disposed to engage the fabric 13 between the discs 100 and 101, as shown in Figs. 4 and 9. These eight rollers 146 are each mounted for free rotation upon a plurality of vertical shafts 150 extending between the arms of the ends 151 of bifurcated bars 152, which are slidably supported to adjust the rollers 146 toward and away from the fabric 13 in the standard 148, which in turn is secured upon the bed plate 45. Each bar 152 is adapted to be clamped in adjusted position by a pair of set screws 153 passing through the standard 148 and engaging in a groove 154 formed in one side of said bar 152. Each roller 146 is also provided with an annular groove 155 which is adapted to straddle the outer edge of the lowermost disc 100.

Three rollers 147 (see Figs. 4 and 10), which are equally spaced about the fabric 13, are each mounted for free rotation on shafts 156 extending between the arms of the bifurcated ends 151 of bars 158 slidably mounted in each of the standards 149. Like the bars 152, each of the bars 158 is provided with a groove 159 within which the bar 158 is clamped in adjusted posi-

tion by set screws 160. The rollers 141 are arranged to engage the fabric at the upper raised ring portion 106 of the cylindrical member 104.

Stationary smoothing out brushes.

A plurality of stationary smoothing out brushes 161 (see Fig. 11) may also be provided to engage the fabric 13 above the cylindrical member 104. Each of the brushes 161 is rigidly mounted on a bar 162 which is adjustably mounted in a bracket 163 to move the brush toward and away from the fabric as desired. The bar 162 in each instance is provided with a groove 164 into which set screws 165 extend to clamp it in its adjusted position. The brackets 163 are each secured upon standards 149 by screws 166 which pass through elongated holes 167 formed in said brackets 163 and are screw-threaded into the standards 149, whereby the respective brushes 161 may be vertically adjusted.

Provision may also be made of means to control the tension or "drag" on the fabric 13 at the disc 95 by disposing an inflatable rubber tube 168 in the groove 96 thereof (see Fig. 12). The cooperating action of the tube 168 and the spring 99 will impose sufficient frictional "drag" depending on the air pressure in the tube 168, which may be adjusted by means of a valve 169.

Operation.

The fabric 13 is loosely packed manually in the folded condition shown in Fig. 2 into the receptacle 17 while the dome 19 is in position. The spreader frame 86 will then be substituted for said dome 19, and the upper end of the tubular fabric will be connected to the take-up mechanism. The motors 27 and 109 will then be started causing the fabric 13 to be slowly rotated and pulled upwardly through the napping mechanism. The outer surface of said tubular fabric will thus be napped successively by the rotating brushes 120 and 128 and by the stationary brushes 161 when used.

One advantage resulting from the use of the present improved machine of this invention is that a long length of tubular knitted fabric may be automatically napped, and the entire napping operation may be minutely controlled by adjustments readily made from the outside of the machine while the latter is set up.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a machine for napping a relatively long length of tubular fabric, a rotatable receptacle for holding a supply of said fabric in collapsed condition, fabric take-up means located above said receptacle, rotatable circular means disposed between said receptacle and said take-up means, over which said fabric is continuously stretched, and a plurality of rotatable napping brushes spaced about the fabric in alignment with said circular means to engage it and nap its surface.

2. In a machine for napping a relatively long length of tubular fabric, a receptacle at the bot-

tom of said machine for carrying a supply of said fabric in collapsed condition, take-up means for the napped fabric at the top of said machine, a plurality of circular fabric-guiding rings between said receptacle and said take-up means, a rotatable napping brush having a flat operating face to engage and nap the exterior surface of said tubular fabric on a flat area, means to adjust said napping brush toward and away from the outer surface of the fabric, and means to rotate said receptacle, said guiding rings and said fabric take-up means in synchronism.

3. In a machine for napping a relatively long length of tubular fabric, a bottom receptacle for carrying a supply of unnaped fabric in tubular collapsed condition, take-up means for the napped fabric at the top of said machine, a plurality of circular fabric supporting and guiding means disposed between said receptacle and said take-up means, a plurality of rotatable brushes having flat end napping surfaces for engaging the exterior of said fabric on flat areas of said fabric, and a second plurality of rotary brushes having cylindrical napping surfaces for engaging said fabric, said cylindrical surface brushes being mounted on axes at right-angles to the axes of said flat-surface brushes.

4. In a machine for napping a relatively long length of tubular knitted fabric, a pair of interior rings to support the interior of said tubular fabric, means to move the fabric in a helical direction, and rotary means having a flat end face in contact with said fabric disposed at spaced intervals about the exterior of said fabric and between said supporting rings for napping it along flat areas thereof.

5. In a machine for napping a relatively long length of tubular knitted fabric, a pair of spaced interior supporting rings over which said fabric is stretched, means to draw the fabric lengthwise over said rings, means to rotate said rings and the fabric supported thereby, means to impose a drag on the fabric to maintain it taut on said circular means, and a plurality of rotatable brushes having flat napping surfaces disposed outside said fabric and located between said rings for continuously napping the outer surface of said fabric along flat areas thereof.

6. In a machine for napping the exterior surface of a tubular knitted fabric, a pair of looped supporting means within said fabric to maintain it in tubular form, means to draw the fabric lengthwise over said supporting means, a rotary brush having a flat inner surface for pressing inwardly upon and napping the exterior surface of said fabric between said looped supporting means, and means to adjust said brush lengthwise along the fabric and toward and away from the surface thereof.

7. In a machine for napping the exterior surface of a tubular knitted fabric, a pair of interior supports for maintaining said fabric in tubular condition, take-up mechanism for continuously drawing the napped fabric over said supports, means to rotate said supports and take-up mechanism as a unit as it is drawn over said supports, a plurality of rotary napping flat-faced brushes located outside said fabric, and means for pressing said brushes inwardly between said supports upon the outer surface of the fabric to nap it on the flat areas thereof.

8. In a machine for napping the exterior surface of a tubular knitted fabric, an interior support for maintaining said fabric in tubular condition, a yieldably-driven take-up mechanism

for the napped fabric, means to continuously rotate said support and take-up mechanism, a plurality of rotary brushes located outside said tubular fabric, each brush having a pinion secured thereto, a circular rack engaging all of said pinions for driving each of said brushes, and means to drive said rack to cause said brushes to continuously nap the exterior of said fabric.

9. In an apparatus for napping the exterior surface of a longitudinally traveling tubular knitted fabric, a continuously rotating central supporting shaft, means connected with said shaft for maintaining said fabric in tubular form, means for napping the exterior surface of said fabric, means to wind up the napped fabric into a cylindrical roll, and an interior ring having a cylindrical portion, a plurality of rollers outside of said fabric for pressing it upon said cylindrical portion to centralize and guide said napping mechanism.

10. In an apparatus for napping the exterior surface of a longitudinally traveling tubular knitted fabric, a continuously rotating central supporting shaft, means connected with said shaft for maintaining said fabric in tubular form, means for napping the exterior surface of said fabric, means to wind up the napped fabric into a cylindrical roll, and an interior ring having a cylindrical portion and a plurality of adjustable rollers outside of said fabric for pressing it upon said cylindrical portion to centralize and guide said napping mechanism.

11. In an apparatus for napping the exterior surface of a longitudinally traveling tubular knitted fabric, a continuously rotating central supporting shaft, means connected with said shaft for maintaining said fabric in tubular form, means for napping the exterior surface of said fabric, means to wind up the napped fabric into a cylindrical roll, and an interior ring having a cylindrical portion and a plurality of vertically and horizontally spaced rollers outside of said fabric for pressing it upon said cylindrical portion to centralize and guide said napping mechanism.

12. In an apparatus for napping a continuously helically moving tubular knitted fabric, means within said fabric to maintain it in tubular condition, a central shaft for supporting said fabric maintaining means, a receptacle secured to the bottom of said shaft for holding a supply of un-napped tubular fabric in collapsed bellows-like condition, a detachable dome member located at the top of said shaft to facilitate the manual

stacking of said un-napped fabric in bellows-like form upon said receptacle, and means to slowly rotate said receptacle and said shaft as a unit.

13. In an apparatus for napping the exterior surface of a continuously helically traveling tubular fabric, interior means to support said fabric, a rotating adjustable member having flat napping means on its end surface for engaging and napping the exterior of said fabric on a flat area thereof, resilient means pressing said fabric inwardly against said support to impose a drag upon the longitudinal movement of said fabric, and an inflatable elastic tube located inside said fabric in alignment with said resilient means to permit the amount of said drag to be accurately adjusted.

14. In a machine for napping tubular knitted fabric which is continuously rotated and moved in a longitudinal direction, a pair of rings to support the interior of said fabric at a pair of spaced annular lines to maintain it in cylindrical form between said lines, means to rotate said fabric support, means to draw the fabric lengthwise over said rings, and a rotary napping member having a flat surface for pressing inwardly upon the exterior surface of said fabric along the cylindrical area thereof between said rings.

15. In a napping machine, a pair of circular rings of the same diameter for supporting the interior surface of a tubular fabric along a pair of spaced circular lines, a coiled spring surrounding said fabric and pressing inwardly upon said fabric between said supporting lines to impose a drag upon the longitudinal movement of said fabric, a second pair of spaced rings spaced from said drag-imposing rings, means for holding said fabric tightly stretched thereover, means to nap the exterior of said fabric, and means to take up the napped fabric.

16. In an apparatus for napping the exterior surface of a continuously helically traveling tubular fabric, interior means to support said fabric at a pair of spaced circumferential lines, a rotating adjustable member having flat napping means on its end surface for engaging and napping the exterior of said fabric on a flat area thereof between said lines, a pair of separated interior rings spaced from said first mentioned fabric supporting means, and resilient means pressing said fabric inwardly between said rings to impose a drag upon the longitudinal movement of said fabric.

HARRY FLEISHER.
